UNITED STATES PATENT OFFICE

HENRY HORAN, OF EAST ORANGE, NEW JERSEY, ASSIGNOR TO HARTFORD CARPET COMPANY, OF HARTFORD, CONNECTICUT.

DESIGN FOR CARPET.

Specification forming part of Design No. **11,384**, dated August 26, 1879; application filed August 2, 1879.
[Term of patent 3½ years.]

To all whom it may concern:

Be it known that I, HENRY HORAN, of East Orange, in the county of Essex and State of New Jersey, have invented a new and original Design for a Carpet, of which the following is a specification.

The accompanying photograph illustrates my new design.

This invention relates to a new design for carpets, oil-cloths, and analogous fabrics; and consists in the novel ornamentation of the groundwork, hereinafter more fully pointed out.

Series, *a a*, of fern-leaves, *b b*, of geranium-like leaves, *c c*, of roses, *d d*, of morning-glories,

and, *e e*, of star-flowers are grouped together and cover the otherwise plain background of the carpet, thereby producing a rich and yet harmonious effect.

I claim—

The design for a carpet, consisting of the groups, *a b*, of leaves and, *c d e*, of flowers, substantially as shown.

The above specification of my invention signed by me this 30th day of July, 1879.

HENRY HORAN.
